UNITED STATES PATENT OFFICE.

LAWRENCE R. QUINN, OF NEWARK, AND ALBERT R. PRITCHARD, OF ROCHESTER, NEW YORK; SAID QUINN ASSIGNOR TO REED MANUFACTURING COMPANY, OF NEWARK, NEW YORK, A CORPORATION OF NEW YORK.

ATTACHMENT FOR WASHBOILERS.

992,247.

Specification of Letters Patent. Patented May 16, 1911.

Application filed February 18, 1911. Serial No. 609,501.

To all whom it may concern:

Be it known that we, LAWRENCE R. QUINN and ALBERT R. PRITCHARD, citizens of the United States, and residents, respectively, of 5 Newark, Wayne county, State of New York, and the city of Rochester, Monroe county, and State of New York, have invented certain new and useful Improvements in Attachments for Washboilers, of which the 10 following is a specification.

The object of this invention is to produce a simple and inexpensive device, consisting of a single piece of sheet-metal, which can be fixed permanently to the cover of a wash- 15 boiler and which combines the functions of a soap-shaver and a hook for hanging the cover upon the body of the boiler.

The invention consists in the device hereinafter described, and defined in the ap- 20 pended claim.

In the accompanying drawings Figure 1 is a transverse section of a wash-boiler cover provided with a device embodying the pres- 25 ent invention, Fig. 2 is a bottom view of said device and a portion of the cover to which it is attached, and Fig. 3 is a section on the line 3—3 in Fig. 1.

In the illustrated embodiment of the invention the combined hook and soap-shaver 30 is formed, by suitable bending operations, from a single, straight strip of sheet-metal. This strip is secured to the inner surface of a boiler-cover of ordinary form, the cover being illustrated as comprising a body 4 35 with a lip 5 which depends within the boiler.

The cover is shown as inverted, in Fig. 1, as this is the position in which the soap- shaver is used.

The outer end 7 of the metal strip is se- 40 cured, by solder or otherwise, to the inner surface of the lip 5 and its extremity is

formed as a hook 6. This hook is used to hang the cover upon the edge of the boiler when the cover is not in use. The intermediate portion 8 of the strip extends inwardly 45 along the inner surface of the cover to form the soap-shaver, and the inner end of the strip is bent to form a foot 9 which is soldered or otherwise secured to the inner surface of the cover. The portion 8 of the 50 strip is inclined, transversely, to the surface of the cover, and is sharpened on one edge 10. The inclination affords clearance so that when a cake of soap is shaved against the edge 10 the shavings will pass freely beneath the shaver and collect in the cover, whence they may be emptied into the boiler. 55

When the cover is in use both the hook and the shaver are concealed within the boiler, but the device is always ready and 60 convenient for use in the performance of either of its functions.

We claim:

In combination with the cover of a wash- 65 boiler, a combined hook and soap-shaver 70 consisting in a single strip of sheet-metal having an outer end formed as a hook and secured to the lip of the cover, an intermediate portion extending along the inner surface of the cover and spaced a short distance therefrom, and a bent portion at the inner end forming a foot secured to the inner surface of the cover, said intermediate portion being transversely inclined to the 75 surface of the cover and being sharpened at the edge nearer said surface.

LAWRENCE R. QUINN.
ALBERT R. PRITCHARD.
